WITNESS:

UNITED STATES PATENT OFFICE

ARTHUR R. DOUGLASS, OF CHARITON, IOWA

SAFETY-RAZOR

Application filed January 18, 1932. Serial No. 587,421.

This invention relates to safety razor and it consists in the novel features hereinafter described and claimed.

An object of the invention is to provide a safety razor of simple structure and which approaches as nearly as possible the free edge straight razor by using a safety roller guard preferably fluted or ridged lengthwise and also a holder for the blade and a roller which insures an accurate assembly of the parts and whereby the razor blade is unobstructed and may be used easily at difficult places with confidence and safety.

A further object of the invention is to provide a tubular handle with a blade holder therein for the purpose of holding the blade when the same is being honed or stropped.

In the accompanying drawing:-

Figure 1 is an edge elevational view of the safety razor.

Figure 2 is a side elevational view thereof.

Figure 3 is a vertical sectional view thereof.

Figure 4 is a detailed sectional view showing the blade thereon.

Figure 5 is a transverse sectional view cut on the line 5-5 of Figure 4.

The safety razor includes a hollow cylindrical handle 1 having a spring 2 located therein. A triangular blade holder 3 slideable in the handle and one end of spring 2 bearing frictionally against one side of the holder 3 for the purpose of retaining the holder at a desired position within the handle. A folded rod 4 is located in the holder 3. The holder 3 is provided at one end with a lug 5 adapted to engage the end of the spring 2 to prevent the holder from being completely withdrawn from the handle. When the holder 3 is extended with relation to the handle 1 as shown in Figure 4 of the drawing the lug 5 comes in contact with the end of the spring 2 and a blade 6 may be inserted between the edges of the holder 3 and the opposite sides of rod 4 so that the said blade may be honed or sharpened in the usual manner.

The handle 1 is threaded internally as at 7 and one end of plate 8 is disposed across the end of the handle and is provided with an inclined portion 9. The blade 6 may be

interposed between the inclined portion 9 and the body of plate 8 shown in Figure 3 of the drawing. A screw 10 passes through the inclined portion 9 and the body of plate 8 and engages with thread 7 or the handle. The plate 8 is provided with a shelf for bracket portion 11 having at its ends upstanding lugs 12 upon which is journalled the roller 13. The roller 13 is provided with a longitudinal corrugated periphery 14. A cutting edge of the blade 6 is disposed along the edges of the lugs 12 and is spaced slightly from the periphery of the roller 13.

When in use the corrugated periphery 14 of the roller 13 will come in contact with the skin and stretch the same and as the blade is moved over the skin the cutting edge thereof removes the hair without injuring the skin.

Having described the invention, what is claimed is:

A razor comprising a holder triangular in cross section having one corner open throughout the length of the holder and the remaining corners closed, a rod folded at a point midway between its length and having opposite side portions fitting within the closed corner portions of the holder, the arrangement being such that the edge of a razor blade may be clamped between the opposite side portions of the rod and the blade snugly received in the open corner of the holder.

In testimony whereof I affix my signature.

ARTHUR R. DOUGLASS.
